UNITED STATES PATENT OFFICE

JESSE A. MARTIN, OF LOS ANGELES, CALIFORNIA

PORTABLE FURNACE

Application filed April 21, 1930. Serial No. 445,871.

This invention relates to gas furnaces for heating large spaces, such as halls, factories, warehouses, motion picture studios, out-of-doors, and the like.

5 The purpose of this invention is to provide a heating unit of large capacity which may be utilized for supplying heat to heat small portions of large space that would require an enormous amount of energy to heat the 10 entire space. In other words, this invention purports to provide a portable heating unit that may be moved about into different parts of a hall, factory, warehouse, motion picture studio or out-of-doors, to supply heat to certain portions of the space where it is most desired. This invention is particularly applicable and finds general usefulness in moving picture studios where great space is required for erecting sets, and where a certain amount 15 of heat is necessary for those participating in the production of a picture.

In erecting sets for shooting scenes in the manufacture of motion pictures, it is at times necessary to use, temporarily, only a small 20 part of a vast enclosure; for instance, a certain set may be located in one corner of a studio building, while the set to be used subsequently is located in the opposite corner. In order to maintain a proper temperature 25 for comfort, it would be necessary to heat the entire studio, but this becomes prohibitive in view of the cost. It is, therefore, an object of this invention to provide a portable heating unit of large capacity which may be moved about from spot to spot to temporarily 30 supply heat in sufficient quantities to maintain a proper temperature locally for those participating in the production of motion pictures.

40 In addition to the above, there is a phenomenon peculiar to motion picture photography that occurs when a scene is shot in cold atmosphere and the setting represents a warm interior, such as a warm ball room full of people. It has been found in practice that if the air is too cold, the breath of those 45 participating in the scene, will condense and photograph, thus producing the incongruous effect of frosty atmosphere in a warm room. It, therefore, may become necessary to heat

a certain part of a set before shooting the scene, in which event, the heat unit may be rolled into the spot to be later photographed, and then rolled out before the picture is taken. It is, therefore, another object of this invention to provide a portable heating unit having 55 flexible gas and electrical connections which permit local movement of the unit to primarily heat a scene before the action of the picture takes place.

60 A noteworthy feature of this invention resides in the fact that the unit is so constructed that the hot air is liberated at the base of the unit and, preferably, travels outwardly therefrom to rise by convection. The heat 65 from the unit is, therefore, imparted to the lower layer of cold air along the floor, and heats the lower zone of cold air first, thus providing an efficient heating unit, in that the hot air is delivered directly at the feet of any 70 persons that may be congregated about the unit.

75 Other objects and advantages will become apparent as the description proceeds in conjunction with the drawings in which—

Fig. 1 is a perspective of the complete unit;

Fig. 2 is a section taken on the line 2—2 of Fig. 3;

Fig. 3 is a section taken on the line 3—3 of Fig. 2; and

Fig. 4 is a diagram of the wiring system used.

80 In its entirety, my device, as best illustrated in Fig. 1, comprises a casing, generally designated A, mounted upon casters 85 shown at B. The casing A may be of any suitable configuration, but in this instance is shown as substantially square, and is provided on the upper end with a hood member designated C, which is shown as being substantially frustro-conical in shape. Mounted upon the hood member C is an air blowing arrangement D. The casing A is provided with handle members, suitably mounted thereon and peripherally spaced therefrom, for the double purpose of moving the unit about, and also of preventing persons from leaning against the hot walls of the casing.

95 The lower part of the shell wall is left open, and is covered with a screening mem- 100

ber E for the purpose of permitting air to flow downwardly and outwardly at this point. Heating means, generally designated F, is provided in the lower part of the casing A for supplying heat to the apparatus.

More specifically describing my apparatus, the foregoing generally designated parts will be taken up in the order set forth. The casing or shell A, as before stated, may be of any suitable configuration, but is illustrated as being square, and is formed by building a frame of angle iron units, such as shown at 12, and mounting within said frame a sheet metal lining 13. The lower part of the sheet lining 13 is stopped short of a base plate 14, as shown at 15, and the aforementioned screening member E is mounted to cover the space. Under certain conditions, the base plate 14 may be dispensed with and the hot air blown directly against the floor, but I have found it preferable to use a plate to prevent scorching of the floor or floor coverings. The top member C is likewise formed of sheet metal, and is suitably mounted upon the upper edge of the lining member 13. As before stated, the shape of the member C is substantially frustro-conical, and has mounted upon the upper open end thereof a screen cage 16 substantially circular in outline. Mounted within the screen cage 16 is the air-blown means D, which comprises a motor 17, suitably mounted in a spider arrangement 18 and carrying a direct connecting fan 19 arranged to blow air substantially in the direction indicated by the arrows 20.

More specifically describing the burner means as apart of the heating means it is shown as comprising a flexible gas conduit 21 which conducts gas or other suitable fuel from a source of supply (not shown) to a valve shown at 22. The gas passes through the valve 22 and into mixing chambers 23 which lead to burners 23' in the interior of the furnace. A stem 24 is provided on the valve 22, operable by the handle 25 of said valve, and operates a conventional switch arrangement shown at 26. A flexible conduit 27 houses a pair of lead wires 28 and 29, which lead from a source of power not shown. The electric circuit passes through the switch 26 and outward through the conduit 30 to a thermostatically controlled switch 31. The switch 31 is interposed directly in a stack 32 which conducts the combusted gases from the interior of a combustion chamber 36. As shown, the thermostatically controlled switch 31 is interposed in series in the circuit from the switch 26 to the motor 17. Under this arrangement, it is clear that the motor 17 operates to blow air only in response to proper temperature in the stack 32. From the structure described, with respect to the valve 22 and the switch 26, it is apparent that the switch 26 closes the circuit to the motor 17 only at the time that the valve 22 is opened.

It is also obvious that the motor 17 will not operate to blow air downwardly through the apparatus until the interior of the heating means F is brought to a proper temperature. It is to be understood that although the thermostatic switch is placed in the stack 32, nevertheless, the temperature of the stack is proportional to the temperature of the heating means F; and it requires only that the thermostatic element be adjusted to compensate for this difference. Therefore, the switch 31 is placed in the stack in order to make it more accessible. Such an arrangement will be appreciated as providing a structure for the purpose described.

Referring to the heating means F, located in the interior of the casing A, it is seen to comprise tubes 33 which extend through a header arrangement 34, positioned in the upper part of the casing A. The tubes 33 are surrounded for a small part of their upper portion beneath the header 34 by concentrically arranged tubes 35 which conduct combusted gases from the combustion chamber 36 into the header arrangement.

The header arrangement 34 leads into a downcast portion 37 that terminates in a lateral extension 38 which passes outwardly through the lining 13 and enters the stack 32. The combusted gases produced in the chamber 36, from the burners 23', pass outwardly substantially in the direction of the dotted arrows 39.

The combustion chamber 36 is provided with a bottom closure plate 40 and a top closure plate 40' through which the tubes 33 extend. It is thus obvious that part of the air propelled by the fan 19 is forced downwardly through the tubes 33 and outwardly through the screen E, the remaining air being forced to flow over and around the exterior of the top plate 40' and the header arrangement 34 until it also passes outwardly through the screen E. This arrangement provides a counter flow of drafts whereby a portion of the cold air is forced downwardly through the hot tubes 33 leading directly through the hot combusted gases, and a part is forced to flow over and around the exterior of the heating means. Such an arrangement will be readily recognized as providing a structure whereby the interchange of heat is most efficient and hot air is delivered at a point where it performs the most efficient service for the purpose of heating, as described in this invention.

Although I have herein described a specific embodiment of my invention, nevertheless I am aware that certain modifications and alterations in the nature of refinements may be resorted to in the process of manufacture that would in no wise depart from the scope of the specification or the purview of the appended claims. It is, therefore, my intention

to include all such modifications and alterations by this disclosure.

I claim as my invention:

1. A portable space heater comprising: a casing having a peripheral opening about the lower portion thereof; a stack connected to said casing; casters mounted upon said casing; heating means in said casing; an electrically actuated blower in the upper end of said casing for blowing cold air downwardly through said heating means and outwardly through said opening; and a thermostatically controlled switch arranged in said stack and adapted to control said blower in response to predetermined temperatures in said stack. 80
2. A space heater comprising: a casing having a peripheral opening about the lower portion thereof; a stack connected to said casing; casters on said casing; heating means in said casing, said heating means including a gas burner and valved means for controlling said burner; an electrically actuated blower in the upper end of said casing for blowing air downwardly through said heating means and outwardly through said opening; a thermostatically controlled switch arranged in said stack and adapted to control said blower in response to predetermined temperatures in said stack; and a second switch in series with said thermostatically controlled switch arranged to be operated simultaneously with said valve. 85
3. A space heater comprising: a casing having a peripheral opening about the lower portion thereof; a stack connected to said casing; casters on said casing; heating means in said casing, said heating means including a gas burner and valved means for controlling said burner; an electrically actuated blower in the upper end of said casing for blowing air downwardly through said heating means and outwardly through said opening; a thermostatically controlled switch arranged in said stack and adapted to control said blower in response to predetermined temperatures in said stack; a second switch in series with said thermostatically controlled switch arranged to be operated simultaneously with said valve; flexible conductors for connecting said second switch to a source of electrical energy; and a flexible conduit for connecting said valve to a source of gas. 90
4. In a portable space heater having casters and heating means: an electrically actuated blower arranged to blow cold air downwardly through said heating means; a pair of switches arranged in series to control said blower, one of said switches being a thermostatically actuated switch arranged to control said blower in response to temperatures of said heating means, the other of said switches being arranged to control said blower in accordance with the control of said heating means. 100
5. A portable space heater comprising: a casing mounted upon casters; heating means in said casing; means for blowing cold air downwardly through said heating means and outwardly circumferentially of the base of 70 said casing. 105
- In testimony whereof, I have hereunto set my hand at Los Angeles, California, this 4th day of April, 1930.
